APPARATUS FOR CHARGING A HORIZONTAL COKE OVEN WITH A RAMMED COAL CHARGE

Hermann Petsch, Recklinghausen, Germany, assignor to firm Carl Still, Recklinghausen, Germany

Application November 14, 1930, Serial No. 495,778,
and in Germany November 16, 1929

11 Claims. (Cl. 202—262)

For charging a horizontal coke oven with a rammed coal cake, it is usual to provide a removable shield at the front end of the bottom plate carrying the cake, i. e. the end which advances into the oven chamber when the charge is inserted therein. This shield has the purpose of supporting the head of the coal cake against the stresses occurring during its insertion. The necessary removal of this shield after the chamber has been charged affords considerable inconveniences and difficulties in working, if the removal is effected through the adjacent door opening, as was formerly always the case. Particles of the coal are then broken off from the end of the cake and fall out of the oven and foul the seating of the door, and special arrangements must be made for consolidating the head of the cake in order to reduce these drawbacks within reasonable limits. Also, if the shield is removed through the door opening, the door must be replaced subsequently, after the complete removal so that the oven chamber is open at this side during the whole process of charging, and this leads to heat loss by cooling and to an objectionable formation of flame and smoke.

The invention obviates all the drawbacks mentioned above and simplifies and facilitates the working by the shield being removed vertically upwards, after the insertion of the cake, through an opening in the oven roof.

Different embodiments of the invention are represented by way of example in the accompanying drawings.

Fig. 1 is a side elevation of one example showing the charged oven chamber in longitudinal vertical section.

Fig. 2 is a front elevation at right angles to that of Fig. 1.

Fig. 3 is an elevation similar to Fig. 1 but showing a modified construction.

Fig. 4 is a plan corresponding to Fig. 3 of the roof of the oven battery.

Figs. 5, 6 and 7 show on a larger scale details of the upper portion of the shield. Fig. 5 is a front elevation, Fig. 6 a vertical section on the line *a*—*b* and Fig. 7 a horizontal section on the line *c*—*d* of Fig. 5.

In Fig. 1 the numeral 1 denotes the oven chamber into which the coal cake 2 on the base 3 of the ramming box is inserted. The rear end of the coal cake 2 is supported by the strongly braced shield 4 and its front end by the removable end or shield 5, which is inserted by pins 6 (Figure 2) in the said base 3. The shield 5 is supported by a chain 7 stretched

along the surface of the coal cake 2 to the rear shield 4. The oven chamber 1 is closed on the side of the shield 5 by the door 8, which is inserted before the commencement of the charging operation directly after the coke of the preceding charge has been discharged.

In the oven roof 9 are charging openings 10 for filling in loose coal, but as the normal charging is effected by inserting the rammed cake, these openings are only provided as a reserve. An opening 11 is also provided in the roof for leading away the gaseous products of distillation through the ascension pipe 12 to the hydraulic main 13 which is placed on one side of the oven.

According to the invention, another opening 14 is provided at the end of the oven chamber 1 where the shield 5 is situated; this opening is vertically over the end position of the shield 5 shown in the drawing and serves for the removal of the shield upwards. The apparatus for carrying out this lifting process comprises as its main elements, a gantry or travelling crane 15 with a running track 16 extending over the whole width of the oven battery and a trolley 17 with a winding drum 18 actuated by a motor 19. The crane 15 runs on two rails 36 on the oven roof 9, parallel to the length of the battery, and is constructed to allow room for the ascension pipe 12 and hydraulic main 13 and also access to the charging holes 10. The drum 18 of the trolley 17 serves for winding up a double rope 20 (see Fig. 2) which is guided over freely rotatable rollers 21 mounted on the top of the trolley 17, and at its free end carries a lifting rod 23 by a likewise mounted roller 22 fixed thereon, the eye 24 of the said rod engaging in a hook 25 on the upper end of the shield 5. A cover 26 for the opening 14 is fastened by a bushing 27 so as to be freely displaceable on the rod 23.

A discharge pipe 28 which acts as a chimney and can rotate about pivots 29 is fastened to the frame of the crane 15 on the side towards the opening 14, so that after the shield 5 has been raised, it can be placed over this opening. In this position, the upper end of the pipe 28 is connected to an extension pipe 30 rigid with the frame.

In order to prevent any escape of the gases, set free on charging, through the uncovered openings 14, a jet of steam or air under pressure can be injected in the usual manner at each opening through nozzles 38, connected to a header 37 extending over the whole length of

the battery. In this case the cover 26 on the rod 23 is unnecessary.

Figs. 5, 6 and 7 show details for holding the shield 5 by the chain 7 and for suspending it by means of the hook 25. At the upper part of the hook 25 there is an inclined portion 31 which, when the rod 23 is lowered, facilitates the insertion of the eye 24 into the hook. Below the root of the hook there is an opening 32 in the plate of the shield 5, into which an iron pin 33, riveted to the body of the shield, projects. The end loop 34 of the chain 7 surrounds this pin 33. When the eye 24 of the rod 23 has been lowered so that it engages from below with the hook 25, then, on raising the rod 23, the eye 24 slides the end loop 34 of the chain 7 upwards over the pin 33, so that the chain 7 springs out through the opening 32 before the eye 24 begins to lift the shield 5. In this way, the shield 5 is engaged by the rod 23 and at the same time released from the chain 7, which would otherwise hinder its being lifted.

In the operation of this apparatus the movable base member 3, with the coal cake or charge 2 resting upon it and held both at its rear and front ends by the shields 4 and 5, is introduced in the usual manner into the oven chamber 1, the door 8 having been already inserted. The opening 14 is uncovered by the removal of its normal closing cover. The trolley 17 has the position shown at the right end of Fig. 1, in which the rod 23 is hanging vertically over the opening 14, being prevented from rotating by the arrangement of the double rope 20. The winding drum 18, actuated by the motor 19, now lowers the rod 23. The cover 26 displaceable on the rod is now automatically sealed centrally upon the opening 14 by the conical formation of its lower side. The cover 26 now ensures that the rod 23 can be guided without oscillation, so that the eye 24, as the rod descends further, meets the inclined portion 31 of the hook 25 and as it descends still further engages correctly in the said hook. The winding drum 18 is now rotated in the opposite direction so as to raise the rod 23. Before the lifting of the shield 5 is commenced, the eye 24 of the rod 23 engages the end loop 34 of the chain and as the raising of the rod 23 is continued, lifts said end loop above the upper part of the pin 33, and thereby releases the chain 7 from its coupling connection with the shield 5. As the lifting is continued the shield 5 is completely removed through the opening 14 from the oven chamber 1 and is brought into its highest position.

The chimney pipe 28 is now swung round until its lower end is over the opening 14. The pipe remains in this position until, after the ramming base 3 has been withdrawn, the oven chamber is completely closed by the insertion of the other door situated opposite to the door 8, in order that the gases, developed during the charging process, should be discharged upwards into the atmosphere without causing inconvenience. The pipe 28 is then again swung away and the opening 14 closed by its normal cover. Simultaneously with these measures the trolley 17, with the shield 5 suspended from it in the highest position, travels along the track 16 of the crane 15 to the opposite side of the oven until it arrives at the position 17' shown in dotted lines. The traversing movement of the trolley 17 is effected with the shield 5 raised as shown at 17'. It is seen, that the under side of the shield is raised so far that it passes not only

over the chimney pipe 28 but also over the above-said ascension pipe 12 and the hydraulic main 13. The cross-section of the frame of the crane 15 must obviously be constructed so as to leave a sufficient free space for the suspended shield 5 as shown by Fig. 2. In the position 17' of the trolley 17, when the shield 5 has been lowered by the winding drum 18, it can be again inserted in the coal charge box 35 of the charging machine disposed on this side. The parts are now again in the initial position for the insertion of a new charge. It is also to be noted that the shield 4 always remains connected with the movable base member 3, and that the chain 7 is rolled up on the drum 44 when the base member 3 is withdrawn from the oven. As this chain 7 is rolled up on the drum 44, and as said drum is mounted upon and withdrawn from the oven with the base member, the chain does not remain in the oven during coking.

In the modified construction shown in Figs. 3 and 4, the winding drum 18 is carried by an apparatus 39 which can travel on tracks 40, 41, and 42, provided on the oven roof, both along one side of the oven, where the shield has been removed, and also along the opposite side of the oven where it is again lowered and also from the one to the other side of the oven, as shown in Fig. 4. The connecting track 41 between the two longitudinal tracks 40 and 42 must obviously lie on the one head end of the oven battery in order that it should not obstruct the structures on the oven roof. This construction is only adapted for an arrangement in which the hydraulic main 13 is, contrary to Fig. 1, placed in the middle portion of the oven battery, as shown in Figs. 3 and 4. An electromagnet 43 can be provided in the apparatus 39 to hold the shield 5, which shield is made of magnetic material such as magnetic iron, in its highest position, in order that on traversing the apparatus 39 it should not be set into swinging motion, the shield being again released when the new position of the apparatus has been attained. The action of the arrangement shown in Figs. 3 and 4 corresponds essentially to the previously described action for the apparatus shown in Figs. 1 and 2. After the rod 23 has been lowered into the opening 14 and has engaged under the hook 25, the shield 5 is lifted to the position shown in Fig. 3 and held by the magnet 43. The apparatus 39 then traverses the track 40, then the connecting track 41 and finally the track 42, so that the position 39' shown in dotted lines in Fig. 3 is attained and the shield 5 is now again lowered and inserted in the coal charge box of the charging machine.

In the last-mentioned case arrangements must be made that the rod 23 can be rotated through 180° relatively to the supporting roller 22, after the position 39' of the lifting device has been attained, in order that the rotation due to the traverse of the apparatus 39 from the one to the other side of the oven can be compensated.

It is obviously not absolutely necessary that the transfer of the apparatus 39 from the track 40 of the one side of the oven to the track 42 of the other side should be effected by a connecting track 41. Instead of this, a travelling platform or similar apparatus for this transport can be used. Also, obviously, instead of the tracks 40 and 42 being arranged within the plane of the oven roof, they might, if required, be arranged so that one or both is or are sup-

ported entirely or partially outside the oven block or the buckstays.

The invention is not restricted to utilizing the special devices shown in Figs. 1 and 2 or 5 Figs. 3 and 4. All otherwise constructed devices are applicable for this purpose in which the shield can be raised through the opening provided in the oven roof, moved from this side of the oven over the oven roof to the opposite 10 side of the oven by any suitable transport means and there again inserted in the coal charge box.

What I claim is:

1. Apparatus of the character described, in combination, a horizontal coke oven having an 15 opening in the roof and an oven chamber, a coal cake holding box including a base and a removable end, and means for removing said end of the box through the opening in the roof.

2. Apparatus according to claim 1, comprising 20 a chimney above the said opening in the oven roof, and a header with nozzles adjacent said opening.

3. Apparatus according to claim 1, comprising also means for transporting, the said end, after 25 removal from the oven chamber, over the oven roof to the opposite side of the oven, and means for replacing it in the coal cake holding box.

4. Apparatus according to claim 1, comprising a travelling crane and trolley thereon for transporting said end, after removal from the oven 30 chamber, to the opposite side of the oven, and a winding drum on said trolley for raising and lowering said end.

5. Apparatus according to claim 1, comprising 35 tracks on said oven roof lying at right angles to the oven chamber a travelling crane adapted to travel on said tracks, a trolley displaceable on said crane parallel to the oven chamber, and a winding drum on said trolley for raising and 40 lowering said end.

6. Apparatus according to claim 1, comprising 45 tracks on said oven roof at right angles to the oven chamber, a travelling crane adapted to travel on said tracks, a trolley displaceable on said crane parallel to the oven chamber, a winding drum on said trolley for raising and lowering said end, and a discharge pipe secured to said 50 crane for carrying away gases escaping through

the opening in the chamber roof on charging said oven chamber.

7. Apparatus according to claim 1, comprising a travelling crane and a trolley thereon for transporting said end, after removal from the oven chamber, to the opposite side of the oven, a winding drum on said trolley for raising and lowering said end which is made of magnetic material, means for raising and lowering the end by said winding drum, and an electromagnet, acting to hold said end against swinging oscillations.

8. Apparatus according to claim 1, comprising 80 tracks on said oven roof at right angles to the oven chamber, a travelling crane adapted to travel on said tracks, a trolley displaceable on said crane, parallel to the oven chamber, a winding drum on said trolley, and means operated by said drum and comprising a pair of lifting ropes for raising and lowering said end.

9. Apparatus according to claim 1, comprising 85 a travelling crane and trolley thereon for transporting said end, after removal from the oven chamber, to the opposite side of the oven, and a winding drum on said trolley, a rod attachable 100 to said end, and ropes operated by said winding drum for raising and lowering said rod.

10. Apparatus according to claim 1, comprising 105 a travelling crane and trolley thereon for transporting said end, after removal from the oven chamber, to the opposite side of the oven, a winding drum on said trolley, a rod attachable to said end, ropes operated by said winding drum for raising and lowering said rod, and a closure member, movably attached to said rod 110 for closing said opening in the oven roof.

11. Apparatus according to claim 1, comprising 115 a chain attached to said end and extending horizontally, over the top of the coal cake, means for raising and lowering said end, said 120 means comprising a winding drum, a lifting rod, ropes operated by said winding drum and attached to said rod, an eye on said rod, a hook on said end adapted to be engaged by said eye, and means by which said eye releases said chain 125 from said end at the commencement of the upward movement of said lifting rod.

CERTIFICATE OF CORRECTION.

Patent No. 1,940,562.

December 19, 1933.

HERMANN PETSCH.

It is hereby certified that error appears in the printed specification of the above numbered patent requiring correction as follows: Page 2, line 37, for "sealed" read seated; page 3, line 24, claim 3, strike out the comma after "transporting"; and line 114, claim 11, strike out the comma after "horizontally"; and that the said Letters Patent should be read with these corrections therein that the same may conform to the record of the case in the Patent Office.

Signed and sealed this 15th day of May, A. D. 1934.

Bryan M. Battey
